DESIGN FOR AN OPHTHALMIC MOUNTING

Roland T. Cook, Southbridge, Mass., assignor to American Optical Company, Southbridge, Mass.,
a voluntary association of Massachusetts

Application December 3, 1938, Serial No. 81,543

Term of patent 14 years

To all whom it may concern:

Be it known that I, Roland T. Cook, a citizen of the United States of America, residing at Southbridge, in the county of Worcester and State of Massachusetts, have invented a new, original, and ornamental Design for an Ophthalmic Mounting, of which the following is a specification, reference being made to the accompanying drawing, forming a part thereof.

Fig. I is a perspective view of an ophthalmic mounting embodying my design;

Fig. II is a fragmentary plan view of the mounting shown in Fig. I; and

Fig. III is a front view of the mounting shown in Fig. I.

The characteristic features of the design are shown in full lines in the drawing.

I claim:

The ornamental design for an ophthalmic mounting, substantially as shown and described.

ROLAND T. COOK.
